THROTTLE

Frederick C. Binnall, River Forest Ill., assignor to
Beatrice W. Binnall, River Forest, Ill.

Application February 24, 1941, Serial No. 380,379

6 Claims. (Cl. 251—20)

This invention relates to throttles, and its object is the production of a new and improved type of throttle which quietly throttles the passage of liquid from a high-pressure portion to a low-pressure portion of a piping system.

Other objects of the invention include the provision of auxiliary devices and elements which co-operate with the principal quieting arrangement of the disclosed new throttle to enable the throttle to operate in substantial silence while delivering water over a wide range of rates of flow from a wide range of supply pressures.

GENERAL DESCRIPTION

The term throttle, as used herein, applies equally to a fixed device and to an adjustable one, although a throttle is usually adjustable, and is usually provided with a seat, enabling it to function as a shut-off valve.

It has long been a problem to construct throttles for use in controlling the flow of liquids, particularly water, without giving rise to the common throttle noises generated in or given off by the liquid in flowing through the throttle throat, and experiencing a pressure drop from throttle inlet to throttle outlet. The noises referred to are sometimes called wire-drawing noises, and are distinct from other noises which may result from a vibration of the parts of a worn or poorly designed valve.

I have found that the throttle noise emitted by water in its high-velocity flow from a high-pressure source arises from the formation and collapse of bubbles within the flowing stream, and that such action can occur only when the high-velocity flow results in cavitation—the production of areas of negative or sub-atmospheric pressure. This is indicated by the observed fact that throttle noises are eliminated entirely when a sufficient back pressure can be imposed on the discharge side of the throttle, even though the supply pressure be increased sufficiently to maintain the original velocity of flow through the throttle. The increased back pressure inhibits the formation of bubbles in the water passing through the throttle.

In view of the foregoing, an object of the invention is the production of a throttle arranged to prevent the high-velocity flow therethrough from forming cavities or low-pressure areas in which noise-generating bubbles can form.

In producing a throttle structure capable of carrying out the last stated object of the invention (the prevention of the formation and consequently the subsequent collapse of bubbles of

gas and other vapor to thereby prevent formation of the accompanying objectionable noise), I prefer to locate the outlet of the throttle to one side of the direct path of the high-velocity discharge flow and to arrange a baffle (conveniently the walls of the throttle casing) which acts to divert the high-velocity discharge jet stream from the outlet, back toward the base of the main jet stream, and to so shape and locate the defining walls that cavitation conditions conducive to the formation of the previously mentioned bubbles are avoided.

By adding to such a device a preliminary throttle upstreamward of the principal throttle above outlined, I have provided a composite throttle arrangement capable of handling supply pressures of over one hundred pounds to the square inch, all without making use of any of the more or less expensive or otherwise unsatisfactory arrangements heretofore used to produce quiet throttling of high-pressure liquids.

Other objects and features of the invention will become more apparent as the description progresses.

This application is a continuation in part of my prior application for Throttling valves, filed March 3, 1937, Serial Number 128,481.

The drawings

30 Referring now to the accompanying drawings, comprising Figures 1 to 7, they show views of various forms and uses of throttle valves constructed according to the features of the invention.

Figure 1 shows a view partly in vertical half-section and partly in vertical quarter-section of an angle-pattern throttle valve A designed especially to act as a control valve or stop for use in connection with a direct-connected metering flush valve for flushing water closets and the like;

40 Figure 2 shows a view similar to Fig. 1 but showing a throttle valve B, which is a desirable modification of the throttle valve A, Figure 1;

Figure 3 shows in vertical section a throttle valve C which employs a specifically different arrangement of parts and is intended for general use, such as in the supply line extending to a lavatory faucet, the shut-off valve of a bath tub, or to the control valve of a shower head, and the like;

50 Figure 4 shows a view, partly in vertical half-section and partly in vertical quarter-section, of the angle-pattern throttle valve D, an improvement on the throttle valve A, Figure 1;

55 Figure 5 shows a throttle valve E constructed according to the principles of the throttle valve

D of Figure 4, but in the so-called straight pattern instead of in the angle pattern;

Figure 6 shows a throttle valve constructed generally according to the principles of the throttle valve D, Figure 4, but designed as a general-purpose throttle valve, as is the throttle valve C, Figure 3;

Figure 7 shows an enlarged view, principally in vertical half-section, of the throttle valve D, Figure 4, with lines and arrowheads indicating principally the paths and directions of flow during throttling.

DETAILED DESCRIPTION

The invention, having been described generally, will now be described in detail, with reference to the drawings.

Figure 1

Referring now particularly to Figure 1, the throttle valve shown therein includes a casing or body 2 having the female-threaded inlet 3 and the male-threaded half-union outlet 4.

Throttle valve A is specifically arranged and designed to operate as a combined throttle valve and shut-off valve in association with a flush valve.

Inlet port 26 permits the flow of water from inlet 3 into conditioning chamber 13, whence the water can pass through outlet 4 to the flush valve or other supplied device. The tapered seat surface 25 surrounds the discharge side of inlet port 26 to constitute the fixed seat of the valve. Throttle 11, preferably of metal or other substance with similar characteristics, has seating member 10 located and disposed therein so as to contact fixed seat 25 annularly to close off the inlet entirely when desired.

Throttle and valve parts 11 and 10 are mounted on adjustment stem 12 for axial movement toward and away from fixed seat 25. Stem 12 has the male-threaded portion 14 which cooperates with the threaded opening through bonnet 17, threaded into the open upper end of casing 2. Stem 12 is provided with annular packing member 21, held under a desired state of compression by packing gland 20. Finish cap 18 may be threadedly secured to the outer enlarged portion of bonnet 17 as indicated. When adjustment of the valve is desired, finish shield 18 may be removed to permit stem 12 to be turned by a suitable tool, inserted in the kerfed end portion 19.

Parts 10 and 11 are held in place on stem 12, against shoulder 22, by retaining nut 5, which is threaded on the lower end of stem 12 to press up against recessed seat member 10. Seat member 10 may be of rubber or other similar material of the desired hardness.

When the available supply pressure admitted to the inlet of throttle valve A is not materially in excess of the required pressure, the throttle valve A may be adjusted by means of stem 12 to a wide-open position, in which the top portion of throttle 11 comes up close to the bottom portion of bonnet 17. In this position of adjustment, the water flows comparatively freely through valve A, with an almost negligible drop in pressure therein. For higher pressures, throttle valve A must be adjusted to a more nearly closed position.

In the illustrated position of adjustment, it is to be noted that the lower flange 6 of the retaining nut 5 coacts with the inside surface of inlet port 26 to form a somewhat restricted annular throat followed by the space 7. Following circular flange 6 and its succeeding space 1,

there is a larger flange 8 which, in the illustrated position of adjustment, coacts with the flaring seat portion 25 to form a second throat portion of mild restriction. There is annular recess or space 9 between flange 8 and the bottom of valve seat insert 10. This space is opposed to and joined with the counterbore 24 around flared seat 25. The portion of cylindrical counterbore 24 not occupied by the adjustable valve and throttle structure constitutes a pre-conditioning chamber.

The annular space between the upper limit of counterbore 24 and throttle 11 constitutes the principal throttle throat, being more restricted, or of less cross-sectional area than any preceding throat. The water therefore emerges in an annular jet into conditioning chamber 13 at the highest velocity which it attains in passing through the device.

The function of annular flanges 6 and 8 is to induce mild but effective successive drops in supply pressure, while the function of the annular recesses or spaces 7 and 9, as well as of the unfilled portion of counterbore 24, is to store substantial amounts of water having no net forward movement, which interacts with the mildly pre-throttled passing stream to extract kinetic energy therefrom, transferring it to local eddying currents wherein it is dissipated in the form of heat. The net result of this is that the velocity of the moving stream is slowed by this interaction to such an extent that a less static pressure is applied to the principal throttling throat, that between seat 11 and the upper limit of the surrounding counterbore 24, than would be the case if the stream passed smoothly from inlet port 26 to the principal throttling throat.

In the illustrated position of adjustment, the high-velocity jet stream emerging from the principal throttling throat passes around throttle 11 in the form of a slightly expanding cone. This stream is directed through conditioning chamber 13 into pocket 16. The jet stream thereupon divides, a part of it turning inwardly, reversing, and passing downwardly along the inwardly protruding portion of bonnet 17, until it comes into contact with the upper face of valve 11, at which point it is diverted radially outwardly, along the upper face of throttle 11, until it comes to the edge 23. At edge 23, the reflected jet stream contacts, and moves upwardly with, the main high-velocity jet stream.

The other portion of the conical stream striking in the pocket 16 is diverted outwardly and downwardly along the inside wall of chamber 2 until it reaches the bottom portion of the chamber opposite the upper end of the counterbore 24, at which point the stream moves radially inwardly to contact and move upwardly with the emerging high-velocity stream and to cause such stream to closely hug the exposed portion of throttle 11.

The returning of the reflected branches of the main discharging stream to the exposed inner and outer bases of the high-velocity jet acts to fill up voids tending to form, and thus prevents the formation of areas sufficiently low in pressure to permit the formation of noise-generating bubbles, whereby the throttling is accomplished in substantial silence.

Observation has shown that it is highly important that the main high-velocity jet stream be diverted all around its periphery and reflected back against the base portion of itself, as previously brought out, and also that all portions

and off-shoots of the high-velocity jet stream are prevented from passing directly out through the outlet 4, for such high-velocity streams usually have sufficient kinetic energy to cause generation of objectionable noise within or beyond the outlet. This result is accomplished by the provision of pocket 16, which receives and reflects the jet streams, baffling them away from the passage through outlet 4. All these jet streams are held within conditioning chamber 13 until stream motions have been largely randomized, and the kinetic energy has been sufficiently converted into heat that the stream flowing out through outlet 4 passes tranquilly at a comparatively uniform and low velocity, whereby noise generation is inhibited, both within conditioning chamber 13 and downstreamward thereof.

It will be observed that the lowermost portion of bonnet 17 is reduced in diameter, except at the wings or baffles 15, to provide a number of spaces 21, around the lower end of the bonnet. Under certain conditions, these spaces have been found beneficial in reducing temporary noises sometimes referred to as "shot" noises which arise especially when pockets of air which have collected in the supply line are carried through with the flowing stream of water. Additionally, the water contained in spaces 21 is set into motion in energy-absorbing eddy currents by the inwardly reflected jet streams moving downwardly along chambers 21.

Throttle 11 is preferably of a maximum diameter slightly smaller than counterbore 24, whereby it cannot catch or bind when the valve is being highly throttled or closed off. The height of throttle 11 is preferably so related to the depth of counterbore 24 that the top surface of the throttle is about flush with the top of the counterbore when the valve is closed off.

Figure 2

Figure 2 is a view of a throttle valve B, generally similar to throttle valve A of Figure 1, and operating generally as described in connection with Figure 1. The additional feature of throttle valve B is that structure has been provided to define the traveling annular pocket 16' at the upper end of conditioning chamber 13', such structure being affixed to and movable with throttle assembly 11', carried on adjustment stem 12'. Valve B is shown in its most fully open position, but is capable of adjustment to its fully seated position as well as to any intermediate position.

In both of the throttle valves illustrated in Figures 1 and 2, it will be observed that the point of break away of the high-velocity principal jet from fixed contact with the side-wall throttle 11 or 11', as well as away from the walls of the counterbore 24 or 24', is at a great angle. That is to say, the top surface of throttle 11, for example, veers away from the side wall of the throttle at sharp edge 23 at an angle slightly greater than ninety degrees to thereby permit the inner reversed, returning jet-driven streams to strike readily at the base of the principal discharging high-velocity jet stream where it breaks away from throttle 11. Similarly, the wall of the casing 2 veers sharply away from the cylindrical wall defining counterbore 24. Shearing, stream-spreading, and similar actions tending to cause noise by creating bubble-generating low-pressure areas, are thus avoided.

It has been found highly important, in the construction of Figures 1 and 2, that the break

away corners 23 and 23' be sharp, and that the top surface of the plug veer away from the side walls at an angle of ninety degrees or greater. The illustrated angle of break away from the side wall of counterbores 24 and 24', with the proportions shown in Figures 1 and 2, has been found to be about as effective as a greater angle.

Figure 3

Figure 3, as previously pointed out, shows a combined throttle and shut-off valve C designed for general use in throttling the flow of water supplied through an opened ball-cock, lavatory faucet, laundry-tray outlet, and the like.

Valve C, shown in its closed-off position, includes a hollow casing 41 having conditioning chamber 40 therein. The female-threaded inlet is shown at 42, and the female-threaded outlet at 43. From inlet 42, a passageway leads through inlet port 59, tapered seat 46, and counterbore 57, to inlet chamber 40, from which outlet passageway 56 leads to outlet 43. Bonnet 52 is threaded securely to the casing as shown and it threaded supports adjustment stem 59, provided at the upper end 55 with a shaped portion suitable for enabling it to be turned by a suitable tool or key. Stem 59 is packed at 53, the packing being held in position by the combined packing gland and lock shield 54.

On the lower end of stem 59, throttle 49 is secured centrally in place by the illustrated construction, being held by the annular seat insert 47, retained in place by flange 50 of retaining screw 44.

When throttle valve C has been opened to permit a throttled flow to occur through outlet 43, the seating portion 47 is withdrawn from engagement with the cooperating body seat 46, to permit such flow to occur. When the outward adjustment has been sufficiently carried out to permit a rate of flow within the range ordinarily used, seating portion 47 has been sufficiently removed from fixed seat 46 that the opening between the seats is larger in area than the opening between the inside wall defining counterbore 57, and throttle 49. The throttle 49 and attached seating portion 47 may at this time be in a position of adjustment generally comparable to the position of adjustment illustrated in Figure 1.

It is to be noted that the side-wall shape of throttle 49 is conical, while throttles 11 and 11' have a side-wall shape somewhat closely approximating a portion of a sphere. The simpler side-wall shape of throttle 49 was found to cooperate best with the simpler associated preliminary throttle arrangement, including head 44 of the retaining screw and the recess or space 45 between head 44 and retaining flange 58. In both cases, one thing in common is to be noted—the principal throttling action occurs as the flowing water is progressively thinned out and brought gradually to its thinnest and highest velocity portion at the point where it emerges into the conditioning chamber (13 in Figure 1; 40 in Figure 3).

In Figure 3, pre-throttling is accomplished between screw head 44 and inlet port 59, or tapered seat 46, depending upon the position of adjustment. The preliminary extraction of energy from the flowing stream to reduce the total head of the water is accomplished by the interaction between this stream and the eddy currents within space 45, and the eddy currents within the preconditioning chamber comprised of the lower portion of counterbore 57.

Figure 4

Figure 4 shows the throttle valve D, in angle-pattern, an improved form of a quiet throttle valve adapted for use as the control valve in association with a flush valve, being preferred principally over Figure 1, for example, in that the upper limit of supply pressure which can be throttled quietly at the rates of flow commonly used is well above one hundred pounds to the square inch with the construction shown in Figure 4, instead of the upper limit of about sixty pounds in the construction shown in Figure 1.

Throttle valve D includes a hollow casing 63 having threaded inlet 62 and half-union outlet 64. In Figure 4, the discharge end of supply nipple 61 is shown threaded into inlet 62, and the upstream end of flush-valve-supply nipple 90 is shown held in union relationship to the outlet of the throttle valve by union nut 89. Between threaded inlet 62 and inlet port 66, there is provided an inlet chamber 65, which could conveniently be eliminated by raising the inlet 62 up toward inlet port 66, except that control valves as customarily used in connection with flush valves have the illustrated locational relationship between the inlet 62 and the outlet 64.

Figures of the selenium type.

The working and assembly opening opposite inlet 62 is closed by bonnet 74. Bonnet 74 contains an adjustment stem 77, kerfed at 76 for adjustment by a screw-driver or a similar instrument, and packed against leakage at 78, the packing being compressed as desired by packing gland 75. Bonnet 74 has the inwardly extending thimble portion 81, provided with internal threads to adjustably hold stem 77. Around the base of thimble portion 81, a cavity 79 may be provided. When the bonnet is produced by casting, cavity 79 may be cored out to thereby save metal. Otherwise, the inner face of bonnet 74, between the threaded periphery and thimble 81, may be finished flat.

In order to permit throttle 72 to be accurately centralized during flow, to the end that the discharged jet stream be of uniform thickness all around, throttle 72 is provided with a stem 82 projecting somewhat loosely into a blind hole extending into the lower end of adjustment stem 77. The depth of this hole is preferably so related to the length of stem 82 that a substantial clearance space 84 is provided between the top face of throttle 72 and the threaded lower end portion 83 of adjustment stem 77. In this way, the bearing point about which throttle 72 and attached stem 82 may turn in aligning accurately with a passing flow is sufficiently far from the throttle, and sufficiently close to the axis of movement that substantial alignment may readily result.

As illustrated, throttle 72, together with angular seat portion 69 and pre-entrant portion 68, are all molded (of comparatively hard rubber or similar substance) onto the lower end of throttle stem 82. The throttle stem 82 may conveniently be made of hexagonal metal rod with a shoulder formed thereon by upsetting at 85 to act as a seal against spewing out of the compound during the throttle-molding and vulcanizing operation. The lower portion 87 may be treated, as by knurling, to give a good grip between the metal and the rubber.

In the event that it is installed in the upright position illustrated for convenience in Figure 4, valve D is a gravity-restored check valve, for

the throttle assembly, including parts 82 and 72, is free to fall by gravity to seated position when no flow is occurring, being raised by the flow, when it occurs, to the illustrated position in 5 which the upper end of throttle stem 82 is stopped by the upper end of the blind hole drilled in adjustment stem 77. To aid in the centralizing operation, the upper end of stem 82 may be chamfered somewhat, preferably at the usual 10 sixty degree drill-point angle.

The throttle valve D is shown in substantially the position of adjustment which, when the supply pressure is at or above one hundred pounds to the square inch, permits a rate of flow of about 15 thirty gallons a minute to pass therethrough and thence through the associated flush valve to a water closet of usual construction. In this position of adjustment, the bottom face of the throttle plug is very nearly level with the bottom 20 of counterbore 88, or just about to emerge from within the confines of angular seat 67. In this position of adjustment, the preliminary throttling stage or throat is formed by the annular 25 clearance space between fixed seat 67 and the lower edge of the short cylindrical portion 68, appended to the bottom of the angular seat portion 69 of the throttle body. The water flows through this preliminary throttling orifice at a 30 moderate velocity, induced by a drop in static pressure of about thirty pounds to the square inch. The immediately succeeding space within counterbore 88 and around seat portions 68 and 35 69 serves as a preconditioning chamber in which the velocity head is largely converted into heat by interaction between the flowing stream and the local eddying currents. It may be pointed out that cavitation, a lowered pressure condition 40 favorable to bubble formation and consequent noise generation, is prevented, within the preconditioning chamber defined by counterbore 88, by the high back pressure, about seventy pounds to the square inch, placed upon the contents of the preconditioning chamber by the 45 restriction represented by the succeeding principal throttle stage.

The slightly spreading, conical, high-velocity jet stream discharged from the principal throttling stage, and passing upward along the conical side walls of plug 72, passes across conditioning 50 chamber 73 into pocket 92 to strike against the lower face of bonnet 74 circularly just inside the threaded periphery. This jet stream thereupon divides, a part of it passing outwardly to the outside wall of pocket 92 to be reflected downwardly 55 to the bottom of chamber 73, and thence inwardly and slightly upwardly along the angularly disposed face 70 to the outside base portion of the main jet stream.

The portion of the main jet stream diverted 60 inwardly in pocket 92, at the circle of its contact with the lower face of bonnet 74, proceeds radially inwardly to strike the exposed outer face of thimble 81, and is there reflected downwardly around thimble 81, to strike the upper face of 65 throttle 72, from which it is again turned outwardly to strike the inside base of the main jet stream.

Figure 5

70 As previously mentioned, the throttle valve E of Figure 5 is a straight-pattern device otherwise similar to the angle-pattern throttle valve D. Figure 4. It includes casing 63', having its female-threaded inlet 62' in axial alignment with the outlet 64'. Principally in order to enable

the device to be constructed with ample water-way for low-pressure operation (when installed in such a location that it must be opened fully, either continuously or at times, to permit a substantially unthrottled flow), the throttle portion is inclined at a small angle to the common inlet and outlet axis, as illustrated. It is to be noted that the downwardly sloping ledge 10', surrounding the counterbore 88', drops away into recess 96 between this ledge and the inside wall of the casing, whereas the two are directly joined together in Figure 4. The recess 96 enables the casing to be made somewhat lighter, and has been shown by tests to have no objectionable adverse effect upon the quiet throttling operation.

Figure 6

The general-purpose throttle valve H, Figure 6, includes a casing 136 having inlet 137 and outlet 138, both female-threaded. It is provided with bonnet 144, containing the customary screw-threaded valve stem, rotatable by wheel handle 145 to control the axial adjustment of throttle 141. Throttle 141 may be generally similar to 72, in Figure 4.

In the closed-off position of this device, angular seat portion 143 contacts with the angular seat portion 142 in the casing to close off the flow entirely. Throttle valve H is shown in a position of adjustment suitable for throttling a comparatively high pressure. In this position of adjustment, pre-throttling occurs as previously described between seat portions 142 and 143, the principal throttling occurring between the tapered surface of part 141 and upper edge of the surrounding counterbore. The discharging high-velocity stream passes across conditioning chamber 140 and into pocket 140a, resulting in the outward and inward jet-stream deflection previously described, pursuant to the quieting action.

In order to insure that the conditioning chamber 140 remains full of water under all conditions of use of this general-purpose device, as well as to assist in the maintenance of a substantial back pressure within conditioning chamber 140 under some of the more severe conditions of use under extremely high pressures, it has been found advantageous to provide an outlet port 139 in a size somewhat less than inlet port 146; that is, substantially less than the nominal inside diameter of the supply pipe to be used. This provision was found to materially assist in the promotion of quieting action under the various conditions of use to which a general purpose valve is subjected.

It will be observed that the tapered seat-portion 143 is faced off flat at the small end of throttle 141, and that no cylindrical nose portion corresponding to portion 68, Figure 4, is provided. With the provision of reduced outlet port 139, such cylindrical nose portion has not been found particularly beneficial.

Figure 7

As previously stated, Figure 7 is an enlarged view, partly in section, of the throttle valve D, Figure 4, the section being taken on line 15-15, Figure 4. The casing 63 and a portion of bonnet 74 are shown in half-section. Outlet 64 shows in full lines immediately above the top surface of throttle 72, and in dotted outline elsewhere.

As in Figure 4, the device D is shown in Figure 7 in approximately the position of adjustment which results in a rate of flow of about

thirty gallons a minute therethrough when the static inlet pressure is at or somewhat above one hundred pounds to the square inch.

Lines with directional arrowheads placed thereon have been drawn to show the principal directions of flow during throttling.

It will be observed that a number of vertical lines 280 extend upwardly through inlet port 86, the outermost ones bending to the left and to the right to pass through the first throttling stage into counterbore 88. It will be understood that the others of lines 280, if they could be properly depicted upon the plane surface of the drawing, would similarly pass through into the counterbore 88, keeping in mind that the flow is occurring all around the annular space between the throttle and the walls defining the passageway in which the throttle is located.

It is to be noted that closed lines 210 are shown within counterbore 88, one at the left and one at the right. These lines depict currents eddying in the directions indicated by the arrowheads thereon. Keeping in mind that the flow is occurring all around the passageway, it will be understood that the flow being depicted by lines 210 is toroidal. This flow occurs because of the viscosity coupling between the flowing stream and the water touching, but lying to one side of, the path thereof. The interaction between the flowing stream and the toroid 210 is such as to slow down the velocity of the stream emerging from the preliminary throttling stage and to thus absorb kinetic energy therefrom, as previously mentioned.

Lines 201, one at the left and one at the right, have been drawn parallel to the side walls of throttle 72, in the plane of the drawing, to depict the section thereat of the conical high-velocity jet stream discharged from the principal throttling stage, represented by the throat defined by the throttle surface 72 and the upper limit of counterbore 88. The two lines 201, it will be understood, represent a cone of water moving all around throttle 72.

It will be observed that the lines 201 branch outwardly and inwardly, in pocket 92 at the upper end of conditioning chamber 73, to form the outwardly branching lines 202 and the inwardly branching lines 207. Lines 202 proceed downwardly until they reach ledge 10 at the bottom of conditioning chamber 73, whereupon they proceed inwardly along this ledge until they contact the outside base portion of the conical jet stream depicted by lines 201. The reversed returning streams depicted by lines 207 act to fill up voids tending to form at the outside base line of breakaway of the principal jets, thus promoting silent action as previously described.

The inwardly turning branches 207 of lines 201 proceed inwardly to the vicinity of thimble 81, whereupon they turn down along the wall of this thimble until they come to the vicinity of the top surface of throttle 72, whereupon they turn and proceed radially outwardly along this surface until they contact lines 201. The lines 201 are representative of the path taken by the inwardly reflected portion of the main jet stream represented by lines 201. These inwardly reflected streams thus strike the inside base portion of the principal high-velocity jet cone right at the point of breakaway from throttle 72, and there fill up the cavities or voids tending to form, and thus act to promote silent throttling action in the manner previously described. The inwardly branched lines 201, which complete the circuit

back to lines 201, are intended to depict water flowing in a toroid inside of the high-velocity conical discharge stream, as the outwardly branched lines 202 similarly depict toroidal movement of water outside of the high-velocity jet cone.

Lines 203 and 204, shown both at the left and at the right of the drawing, are intended to depict toroidally moving films of water lying successively within the principal toroid defined by lines 201 and 202. Similarly, lines 206 and 205, are intended to depict toroidal movement of water films inside the toroid indicated by lines 201 and 207. The inner toroids of movement, it will be understood, are viscosity driven, or friction driven, each by the next successive outer one, the action being as previously noted in connection with the toroid depicted by lines 210 within counterbore 88.

Keeping in mind that jet velocities up to or higher than one hundred feet a second exist in throttling devices handling pressures around one hundred pounds to the square inch, it will be appreciated that the particles of water within conditioning chamber 73 move within the toroidal paths above discussed at much higher velocities than are ordinarily associated with the movement of water through pipes. At these high velocities, the action and interaction between the adjacent films of water result in much mixing and intermixing of fast-moving and slow-moving water within a small space, resulting in the quick extraction of energy from the moving streams to permit the water to flow placidly through outlet 64.

It may be further noted that lines 208 indicate toroidal movement of water within the annular bonnet cavity around the base of thimble 81, and that lines 209 depict a similar toroidal movement of water adjacent the exposed threaded portion of the adjustment stem.

I claim:

1. A silent throttling-valve device comprising the combination of a casing having a conditioning chamber, an outlet port communicating therewith, an inlet port, a valve seat surrounding the inlet port, and a cylindrical counterbore surrounding the valve seat and opening into the conditioning chamber, said valve seat being of greater diameter than the inlet port and said counterbore being of greater diameter than said valve seat and said valve seat being located between the inlet port and the counterbore, and a valve member adjustable toward and from the valve seat axially thereof, said valve member including a main tapered throttling portion so located and dimensioned as to form with the edge of the cylindrical counterbore wall at the entrance to the conditioning chamber a main restricted throttling throat, when the valve is slightly opened, a valve-seat-engaging portion, and a secondary throttling portion so located and dimensioned as to form with the inlet port and valve seat a secondary throttling throat, when the valve is slightly opened, less restricted than the main throat and located upstream therefrom.

2. A silent throttling-valve device comprising the combination of a casing having a conditioning chamber, an outlet port communicating therewith, an inlet port, a valve seat surrounding the inlet port, and a cylindrical counterbore surrounding the valve seat and opening into the conditioning chamber, said valve seat being of greater diameter than the inlet port and said counterbore being of greater diameter than said valve seat and said valve seat being located be-

tween the inlet port and the counterbore, and a valve member adjustable toward and from the valve seat axially thereof, said valve member including a valve-seat-engaging portion seating on said valve seat when the valve is closed, a main tapered throttling portion located downstream from the valve-seat-engaging portion and so located and dimensioned as to form with the edge of the cylindrical counterbore wall at the entrance to the conditioning chamber a main restricted throttling throat when the valve-seat-engaging portion is spaced slightly from the valve seat, whereby an annular liquid jet is directed into said conditioning chamber substantially parallel to the wall of said main tapered throttling portion, and a secondary throttling portion located upstream from the valve-seat-engaging portion and so located and dimensioned as to form with the inlet port and valve seat a secondary throttling throat, less restricted than the main throat, when the said valve-seat-engaging portion is slightly spaced from said valve seat, and an enlargement of the passage between said throats, whereby the liquid flow is partially throttled preliminarily before reaching said main throat.

3. A silent throttling-valve device comprising the combination of a casing having a conditioning chamber, an outlet port communicating therewith, an inlet port, a valve seat surrounding the inlet port, and a cylindrical counterbore surrounding the valve seat and opening into the conditioning chamber, said valve seat being of greater diameter than the inlet port and said counterbore being of greater diameter than said valve seat and said valve seat being located between the inlet port and the counterbore, and a valve member adjustable toward and from the valve seat axially thereof, said valve member including a valve-seat-engaging portion seating on said valve seat when the valve is closed, a main tapered throttling portion located downstream from the valve-seat-engaging portion and so located and dimensioned as to form with the edge of the cylindrical counterbore wall at the entrance to the conditioning chamber a main restricted throttling throat when the valve-seat-engaging portion is spaced slightly from the valve seat, whereby an annular liquid jet is directed into said conditioning chamber substantially parallel to the wall of said main tapered throttling portion, and a secondary throttling portion located upstream from the valve-seat-engaging portion and so located and dimensioned as to form with the inlet port and valve seat a secondary throttling throat, less restricted than the main throat, when the said valve-seat-engaging portion is slightly spaced from said valve seat, and an enlargement of the passage between said throats, whereby the liquid flow is partially throttled preliminarily before reaching said main throat, the wall of said conditioning chamber opposite to said counterbore being so formed and located as to reflect and divert said annular jet along toroidal circulation paths toward the wall of the conditioning chamber which includes the counterbore.

4. A silent throttling-valve device comprising the combination of a casing having a conditioning chamber, an outlet port communicating therewith, an inlet port, a valve-seat surrounding the inlet port, and a cylindrical counterbore surrounding the valve seat and opening into the conditioning chamber, said valve seat being of greater diameter than the inlet port and said

counterbore being of greater diameter than said valve seat and said valve seat being located between the inlet port and the counterbore, and a valve member adjustable toward and from the valve seat axially thereof, said valve member including a valve-seat-engaging portion seating on said valve seat when the valve is closed, a main tapered throttling portion located downstream from the valve-seat-engaging portion and so located and dimensioned as to form with the edge of the cylindrical counterbore wall at the entrance to the conditioning chamber a main restricted throttling throat when the valve-seat-engaging portion is spaced slightly from the valve seat, whereby an annular liquid jet is directed into said conditioning chamber substantially parallel to the wall of said main tapered throttling portion, and a secondary throttling portion located upstream from the valve-seat-engaging portion and so located and dimensioned as to form with the inlet port and valve seat a secondary throttling throat, less restricted than the main throat, when the said valve-seat-engaging portion is slightly spaced from said valve seat, and an enlargement of the passage between said throats, whereby the liquid flow is partially throttled preliminarily before reaching said main throat, the wall of said conditioning chamber opposite to said counterbore being so formed and located as to reflect and divert said annular jet along toroidal circulation paths toward the wall of the conditioning chamber which includes the counterbore, and the last-mentioned wall being so formed as to direct the reflected liquid toward the base of said annular jet as it emerges from the main throttling throat.

5. A silent throttling-valve device comprising the combination of a casing having a conditioning chamber, an outlet port communicating therewith, an inlet port, a valve seat surrounding the inlet port, and a cylindrical counterbore surrounding the valve seat and opening into the conditioning chamber, said valve seat being of greater diameter than the inlet port and said counterbore being of greater diameter than said valve seat and said valve seat being located between the inlet port and the counterbore, and a valve member adjustable toward and from the valve seat axially thereof, said valve member including a valve-seat-engaging portion seating on said valve seat when the valve is closed and a

5 main tapered throttling portion located downstream from the valve-seat-engaging portion and so located and dimensioned as to form with the edge of the cylindrical counterbore wall at the entrance to the conditioning chamber a main restricted throttling throat when the valve-seat-engaging portion is spaced slightly from the valve seat, whereby an annular liquid jet is directed into said conditioning chamber substantially parallel to the wall of said main tapered throttling portion, the wall of said conditioning chamber opposite to said counterbore being so formed and located as to reflect and divert said annular jet along toroidal circulation paths toward the wall of the conditioning chamber which includes the counterbore.

10 6. A silent throttling-valve device comprising the combination of a casing having a conditioning chamber, an outlet port communicating therewith, an inlet port, a valve seat surrounding the inlet port, and a cylindrical counterbore surrounding the valve seat and opening into the conditioning chamber, said valve seat being of greater diameter than the inlet port and said valve seat being located between the inlet port and the counterbore, and a valve member adjustable toward and from the valve seat axially thereof, said valve member including a valve-seat-engaging portion seating on said valve seat when the valve is closed and a main tapered throttling portion located downstream from the valve-seat-engaging portion and so located and dimensioned as to form with the edge of the cylindrical counterbore wall at the entrance to the conditioning chamber a main restricted throttling throat when the valve-seat-engaging portion is spaced slightly from the valve seat, whereby an annular liquid jet is directed into said conditioning chamber substantially parallel to the wall of said main tapered throttling portion, the wall of said conditioning chamber opposite to said counterbore being so formed and located as to reflect and divert said annular jet along toroidal circulation paths toward the wall of the conditioning chamber which includes the counterbore, and the last-mentioned wall being so formed as to direct the reflected liquid toward the base of said annular jet as it emerges from the main throttling throat.

FREDERICK C. BINNALL.

CERTIFICATE OF CORRECTION.

Patent No. 2,334,686.

November 16, 1943.

FREDERICK C. BINNALL.

It is hereby certified that error appears in the printed specification of the above numbered patent requiring correction as follows: Page 1, second column, line 27, for "Serial Number 128,481" read --Serial Number 128,841--; page 3, first column, line 51, Figure 2, for "is" second occurrence, read --its--; page 4, first column, line 27, Figure 4, strike out the syllable and words "fiers of the selenium type.;" and that the said Letters Patent should be read with this correction therein that the same

may conform to the record of the case in the Patent Office.

Signed and sealed this 21st day of December, A. D. 1943.

Henry Van Arsdale,

Acting Commissioner of Patents.
